UNITED STATES PATENT OFFICE.

AUGUST J. BRUDER, OF HOLLY, MICHIGAN.

TOILET SEAT.

Application filed August 30, 1926. Serial No. 132,348.

My invention aims to provide a durable sanitary ventilating toilet seat that may be sold with the idea of substituting it for ordinary wooden and unsanitary toilet seats.

5 My invention still further aims to provide a toilet seat made of Bakelite or other phenolic condensation products, and in the rear portion of the seat is firmly anchored a ventilating member adapted to communicate 10 with an exhaust flue or conduit leading to the atmosphere. The seat is designed to constantly provide an air inlet space between the seat and the upper edges of the bowl so that when the seat is occupied air may pass 15 under the seat and enter the exhaust flue, thus carrying off obnoxious odors.

My invention will be hereinafter specifically described and then claimed, and reference will now be had to the drawing, 20 wherein

Figure 1 is a plan of the toilet seat;

Fig. 2 is a longitudinal sectional view of the same in connection with a conventional form of bowl or hopper;

25 Fig. 3 is an enlarged plan of a ventilating member forming part of the seat, and

Fig. 4 is a view of the rear end of said ventilating member.

In the drawing, the reference numeral 1 30 denotes a conventional form of hopper or bowl having the usual rearward extension 2 provided with apertured ears 3 to which a seat may be pivotally connected by pintles, bolts or the like. In this instance, I show the 35 apertured ears 3 connected by a transverse pin or pintle 4 adapted for pivotally holding the apertured lugs 5 of a toilet seat 6 which is of the ordinary and well known shape and size. The apertured lugs 5 project upwardly 40 and rearwardly from the sides of a transverse enlargement 7 at the rear edge of the seat 6 and its enlargements is of greater depth than the seat 6 so that the rear end of the seat will be elevated relative to the bowl 1. In order 45 that the seat 6 may remain horizontal relative to the bowl 1 there are depending pegs or supports 8 at the front end of the seat and these pegs cooperate with the enlargement 7 in maintaining the seat in spaced relation 50 to the upper edge of the bowl 1, so that there will be an air inlet opening 9 between the seat and the bowl.

The seat 6 is preferably made of Bakelite and the pegs 8 may be made of similar material or rubber and attached to the bottom of

the seat 6. It is preferable to use rubber or some resilient material to somewhat cushion the seat 6 when it is placed in an active position relative to the bowl. The pegs 8 may be of greater depth than the enlargement 7 so as to be placed under compression when the seat is occupied, also to prevent the enlargement 7 from being injured should it violently contact with the bowl when the seat is lowered from a raised position.

55 In the rear enlargement 7 of the seat 6 is anchored a metallic ventilating member 10 somewhat in the form of a box that has end walls 11 tapering outwardly from the front end of the member to the rear end thereof, the front end of the member being open and concave, as at 12, so as to conform to the opening wall 13 of the seat. The box-like ventilating member is embedded in the enlargement 7 and has its upper and lower walls 70 apertured, as at 14 so that the Bakelite composition of the seat may enter the upper and lower walls of the ventilating member as clearly shown in Fig. 2, and thus anchor the ventilating member in the seat as though it 75 was an integral part thereof. Further anchorage is secured by means of curved apertured arms 15 carried by the end walls 11 of the ventilating member and extending into the composite seat, as shown by dotted lines 80 in Fig. 1. Since the enlargement 7 is of greater depth than the seat 6 with the member 10 approximating the depth of the seat, it becomes necessary to provide the front edge of the member 10 with an inclined wall 85 90 16, which is also apertured. This wall cooperates with other walls of the ventilating member in providing an air inlet opening 17 and the rear end of the member 10 is adapted to communicate with a suitable exhaust flue 95 18, which in the present instance, is mounted on the rear portion of ledge 2 of the bowl 1 between the ears 3 and under the pin 4.

When the seat 6 is occupied air may pass under the seat, enter the opening 17 and pass 100 through the member 10 into the exhaust flue 18, thus carrying off odors from the bowl.

I attach considerable importance to the seat 6 being made of one piece of sanitary and durable material with the ventilating member 10 embedded therein. As an article of merchandise the seat may be purchased and readily substituted for other seats.

One embodiment of my invention has been illustrated, but it is to be understood that 105 110

the construction of the seat is susceptible to such changes as are permissible by the appended claims.

What I claim is:—

- 5 1. The combination of a toilet seat, a box-like ventilating member embedded in the rear portion of said seat, curved arms carried by said ventilating member and extending into the toilet seat.
- 10 2. The combination with a bowl, of a toilet

seat hingedly connected thereto, said toilet seat having a rear portion of greater depth than the remaining portion of said seat so as to provide an air space between said bowl and seat, and a ventilating member embedded in the rear portion of said seat to receive air from under said seat. 15

In testimony whereof I affix my signature.

AUGUST J. BRUDER.
